US00D881336S

(12) **United States Design Patent** (10) **Patent No.:** **US D881,336 S**
Dani et al. (45) **Date of Patent:** **** Apr. 14, 2020**

(54) **FILTER CORE**

- (71) Applicant: **Brita LP**, Oakland, CA (US)
(72) Inventors: **Nikhil P. Dani**, Pleasanton, CA (US);
Russell Bell, Pleasanton, CA (US)
(73) Assignee: **Brita LP**, Oakland, CA (US)
(**) Term: **15 Years**
(21) Appl. No.: **29/657,747**
(22) Filed: **Jul. 25, 2018**

Related U.S. Application Data

- (63) Continuation of application No. 15/756,747, filed as application No. PCT/IB2016/001495 on Sep. 27, 2016.
